O. E. JORGENSEN

PISTON COOLING DEVICE

Filed July 22, 1924

FIG. 2.

FIG. 1.

FIG. 3

UNITED STATES PATENT OFFICE.

OLAV ESKIL JORGENSEN, OF FOREST HILLS, NEW YORK, ASSIGNOR TO WORTHINGTON PUMP AND MACHINERY CORPORATION, OF NEW YORK, N. Y., A CORPORATION OF VIRGINIA.

PISTON-COOLING DEVICE.

Application filed July 22, 1924. Serial No. 727,489.

This invention relates to that class of piston cooling devices for internal combustion engines and the like, in which cooling liquid is circulated through the piston by a telescoping pipe system, the object of the invention being to provide an improved construction for avoiding injury from misalignment or irregularity of movement between the telescoping parts in the operation of the engine and avoiding objectionable leakage of the cooling liquid.

The invention includes a novel mounting for the stationary portion of the telescoping system by which all this portion, including the stuffing boxes for the movable pipes, is carried on a flexible or universal joint, so that the whole stationary portion of the telescoping system swings with the movable pipes for compensation of misalignment of irregular movement. The invention includes also certain specific features of construction and combinations of parts as particularly pointed out hereafter.

For a full understanding of the invention a detailed description of a construction embodying all of the features of the same in a preferred form will now be given in connection with the accompanying drawings forming a part of this specification and the features forming the invention then be specifically pointed out in the claims.

In the drawings—

Figure 1 is an elevation partly in section of an internal combustion engine cylinder and piston equipped with the device;

Figure 2 is a vertical section of the telescoping system on a larger scale, and

Figure 3 is a detail section on the line 3—3 of Fig. 2.

Referring to the drawings, the invention is shown as applied to a double-acting vertical cross-head engine, but it will be understood that it is equally applicable to single-acting engines and to types of engines other than cross-head engines. In the construction shown, A is the main frame of the engine, B the cylinder frame, C, C' the outer and inner cylinders in which move the outer and inner pistons D, D' of the double-act-

ing engine, the pistons being connected so as to form a single member actuated by piston rod E connected to cross-head F having pitman G, all of which parts may be of any suitable construction. Each of the pistons D, D' is provided with a cooling chamber 10 in its head to which cooling liquid is supplied from a passage 11 in the piston rod enclosing a central pipe 12, through which the cooling water returns from the pistons. The passage 11 opens directly into the chamber 10 of piston D, and for cooling the piston D' a dam 1 is used in passage 11 which compels the supply liquid in passage 11 to circulate to and from the cooling chamber 10 in piston D' through passages 2, as shown in dotted lines in Fig. 1. The passage 11 and pipe 12 extend to the cross-head F and there are connected, respectively, by passages 13, 14 in bracket 15 carried by the cross-head, with supply pipe 16 and discharge pipe 17, which are secured in and move with the bracket 15 and cross-head F, these pipes being the movable pipes of the telescoping system. In the construction shown, the liquid is supplied through passage 11 and discharged through central pipe 12, and this is preferable, but it will be understood that the connections may be reversed, and liquid supplied to the pipe 12 and discharged through the passage 11, both methods of supply and discharge being well known in the art.

Pipes 16, 17 telescope, respectively, through pipes 18, 19 which form the stationary pipes of the telescoping system, these pipes 18, 19 carrying at their ends stuffing boxes 20 through which the movable pipes 16, 17 move. The stationary pipe 18 has a head 21 forming a chamber connected with pipe 22 through which the cooling liquid is supplied, and from which opens pipe 23 extending into the movable pipe 16 and preferably formed at its inner end with a head or bush 3 having an easy fit in the pipe 16. Any leakage past the head 3 flows over the inner end of the pipe 16 and is drained off through drain pipe 24 connecting with pipe 18 adjacent to the stuffing

box. The stationary pipe 19, in which discharge pipe 17 telescopes, has an outlet 25 through which the water is discharged in any suitable manner, and this pipe 19 carries a head 26. The heads 21, 26 of pipes 18, 19 are formed with stems 27 by which the stationary pipes are supported by universal joints 28 on cylinder frame B, these joints being shown as ball and socket joints, although any suitable form of universal or similarly flexible joint may be used. Side pressure on the stuffing box is thus prevented and the leakage and packing wear resulting from this avoided. Provision is preferably made, however, for removing and collecting cooling liquid or lubricating oil which may adhere to the pipes 16, 17, or cooling liquid which may leak along these pipes through stuffing boxes 20, and in the construction shown scrapers 29 are provided acting on the pipes 16, 17 on their movement in opposite directions, these scrapers being carried by a slide 30 free to move sidewise with the pipes 16, 17 in support 31 on the engine frame A. Most of the cooling liquid will be discharged on the downward movement of the pipes 16, 17, by the upper scrapers 29, and these scrapers deliver the liquid removed from pipes 16, 17 to trough 4 formed in the support 31, from which the liquid may be piped off as desired. The lower scrapers 29 take care of any water or lubricating oil that may collect on the pipes below support 31.

It will be seen that the invention provides a very simple and efficient telescoping system, providing against objectionable leakage by the use of stuffing boxes between the telescoping pipes, while all misalignment or irregularity of movement of the movable pipes is permitted without injury to the system, by the freedom of movement with the movable pipes of the entire stationary portion of the telescoping system, including the stationary pipes and stuffing boxes.

It will be understood that the invention is not to be limited to the specific construction or arrangement of parts shown, but that many changes in the construction may be made while retaining the invention defined by the claims.

What is claimed is:

1. An engine piston cooling system, having a liquid-conducting pipe moving with the piston, a stationary pipe within which the moving pipe telescopes, a stuffing box between the moving and stationary pipes, liquid connections for the stationary pipe, and a flexible mounting for the stationary pipe and stuffing box permitting the stationary pipe and stuffing box to move sidewise with and in parallelism with the moving pipe.
2. An engine piston cooling system, having liquid supply and discharge pipes mov-

ing with the piston, stationary pipes within which the moving pipes telescope, stuffing boxes between the moving and stationary pipes, supply and discharge connections for said stationary pipes, and flexible mountings 70 for the stationary pipes and stuffing boxes permitting the stationary pipes and stuffing boxes to move sidewise with and in parallelism with the moving pipes.

3. An engine piston cooling system, having a liquid supply pipe moving with the piston, a stationary pipe within which the moving pipe telescopes, a stuffing box between the moving and stationary pipes, connections for supplying liquid to the stationary pipe, a flexible mounting for the stationary pipe and stuffing box permitting the stationary pipe and stuffing box to move sidewise with and in parallelism with the moving pipe, and a scraper outside the stuffing box for removing liquid from the moving pipe, said scraper being movable sidewise with the moving pipe.

4. An engine piston cooling system, having liquid supply and discharge pipes moving with the piston, stationary pipes within which the moving pipes telescope, stuffing boxes between the moving and stationary pipes, supply and discharge connections for said stationary pipes, flexible mountings for 95 the stationary pipes and stuffing boxes permitting the stationary pipes and stuffing boxes to move sidewise with and in parallelism with the moving pipes, and scrapers for said moving pipes outside the stuffing boxes for removing liquid from the moving pipes, said scrapers being movable sidewise with the moving pipes.

5. An engine piston cooling system having a stationary pipe extending generally parallel to the piston rod of the engine, a flexible mounting for that end of the stationary pipe remote from the crank shaft of the engine, a stuffing box carried by the opposite end of the stationary pipe, a movable pipe having its end nearest the crank shaft rigidly connected to move with the piston and having its other end extended through the stuffing box and into the stationary pipe, and connections for supplying liquid to the 1 stationary pipe.

6. In an engine piston cooling system, comprising a hollow piston, a piston rod having passages for the supply and discharge of cooling liquid, and a cross-head having liquid passages connected with the respective passages of the piston, the combination, with a bracket secured to the cross-head and having liquid passages in communication with the respective passages of the cross-head, a pair of movable pipes, one for each passage, secured by their ends nearest the crank shaft to the bracket and movable therewith, a pair of stationary pipes into which the respective movable pipes

telescope, each stationary pipe being provided with a stuffing box at its end nearest the crank shaft, in which stuffing box its
5 movable pipe slides, each stationary pipe being provided at its end remote from the crank-shaft with a flexible mounting connecting it to the engine frame, means for

supplying water to one stationary pipe, and means for discharging water from the other stationary pipe.

10

In testimony whereof, I have hereunto set my hand.

OLAV ESKIL JORGENSEN.
